(57) **CLAIM**

The ornamental design for a container and lid, as shown and described.

DESCRIPTION

FIG. 1 is an isometric view of a top, front, and right side of an ornamental design for a container and lid according to the present invention;

FIG. 2 is a rear elevational view of the container and lid taken generally along the view lines 2—2 of FIG. 1, a left side elevational view perpendicular to the rear elevational view being identical thereto;

FIG. 3 is a front elevational view of the container and lid taken generally along the view lines 3—3 of FIG. 1;

FIG. 4 is a right side elevational view of the container and lid taken generally along the view lines 4—4 of FIG. 1; and,

FIG. 5 is a plan view of the container and lid of FIG. 1. The bottom features of the container and lid form no part of the claimed design.
